United States Patent Office

Des. 183,117
Patented July 1, 1958

183,117

COMBINED LENS AND VENTILATOR COVER FOR A RECESSED LIGHT AND FAN UNIT

George Coleman, Glencoe, and Robert Podall, Highland Park, Ill., assignors to Berns Air King Corporation, Chicago, Ill.

Application May 27, 1957, Serial No. 46,356

Term of patent 14 years

(Cl. D48—16)

Fig. 1 is a plan view of a combined lens and ventilator cover for a recessed light and fan unit showing our new design;

Fig. 2 is a side elevational view thereof;

Fig. 3 is an end view thereof; and

Fig. 4 is a cross section taken on the line 4—4 of Fig. 1 and viewed in the direction indicated.

We claim:

The ornamental design for a combined lens and venti-

lator cover for a recessed light and fan unit, substantially as shown.
